CIGARETTE MACHINE

Erdman Rudolph Hiebert, Sardis, British Columbia, Canada

Application December 12, 1940, Serial No. 369,872

21 Claims. (Cl. 131—59)

This invention relates to a machine for making cigarettes.

An object of the present invention is the provision of a small machine for making cigarettes.

Another object is the provision of a machine for home use which is capable of making cigarettes comparable in appearance and structure to the manufactured cigarettes now on the market.

Another object is the provision of a cigarette machine for home use which is capable of easily and rapidly making the cigarettes.

A further object is the provision of a cigarette machine which will reduce materially the cost of cigarette smoking.

A further object is the provision of a cigarette machine for home use with which it is possible to regulate the packing of the tobacco in the cigarettes, the range extending anywhere from a loosely packed to a tightly packed cigarette.

Yet another object is the provision of a machine for turning out perfect cigarettes made of any tobacco the operator may desire to use.

A still further object is the provision of a machine for home use in which pure tobacco may be used to turn out cigarettes with all the advantages as to appearance and structure of manufactured cigarettes, without the disadvantages thereof occasioned by the addition of foreign substances to the tobacco in these latter cigarettes.

Yet another object is the provision of a machine for producing cigarettes having the paper spirally wound therearound, thus enabling the tobacco to be packed more tightly than in the common type of cigarette.

Still another object is the provision of a device of the character described which is neat, compact, relatively simple in construction, and which may be easily operated.

With these and other objects in view, the present invention consists essentially of a cigarette machine comprising a base, means on the base for forming a spiral tube of cigarette paper, and means for injecting tobacco into the completed tube, as more fully described in the following specification and illustrated in the accompanying drawings, in which

Figure 1 is a plan view of the cigarette machine with the feed hopper removed,

Figure 2 is a side elevation of the machine,

Figure 3 is a longitudinal section taken on the line 3—3 of Figure 1,

Figure 4 is a cross sectional view taken on the line 4—4 of Figure 1,

Figure 5 is a cross sectional view taken on the line 5—5 of Figure 1,

Figure 6 is a cross section taken on the line 6—6 of Figure 1,

Figure 7 is a plan view of the feed hopper,

Figure 8 is an elevation, partly in section, of an alternative worm feed for the machine, and

Figure 9 is an end elevation of the alternative worm feed.

Referring more particularly to the drawings,

10 is a base having a suitable end support 11 with side supports 12 and 13 on each side thereof 15 while another support 14 is spaced inwardly from the support 11. These supports may be in the form of walls projecting upwardly from the base 10, as shown, or they may be any desired form of frame work. For the sake of convenience, the end 15 of the base 10 will hereinafter be referred to as the feed end and the end 16 as the discharge end.

15 A barrel 17, the diameter of which is substantially equal to that of an ordinary cigarette, projects outwardly from the support 14 adjacent the top thereof and extends longitudinally of the base towards but terminating short of the discharge end 16, the outer end of said barrel being indicated by the broken line 18 in Figure 3. A 20 worm 20, preferably tapered, has an enlarged head 21 at its larger end which is journalled in a bearing 22 carried by the end support 11 near the top thereof, said bearing being in line with the barrel 17. This worm has a contrate gear 23 on its outer end while the opposite end of the spiral projects into the barrel 17.

25 The worm 20 is rotated in any suitable manner and in Figure 1, the contrate gear 23 meshes on one side of the worm with a gear 24 mounted on a stub shaft 25 which is journalled in a bearing 26 carried by the end support 11. The gear 24

30 meshes with a gear 27 mounted on a shaft 28 extending transversely of the machine beneath the worm 20 and journalled in bearings 30 and 31 carried by the side supports 12 and 13, respectively. Another gear 32 mounted on the shaft 28 on the opposite side of the worm, meshes with a gear 33 mounted on a shaft 34 mounted in a bearing 35 carried by the end support 11,

35 said shaft extending freely through the side support 12 and having a crank 36 on its outer end. With this arrangement, the worm 20 turns in the same direction as the crank 36 is turned. A cover 37 is removably mounted on the support 11 over

40 the gear 23 in any suitable manner, such as by

being internally threaded and screwed on to a threaded collar 38 extending around said gear.

A relatively large hopper 42 is removably mounted on the supports 11, 12, 13 and 14, the sides of said hopper converging inwardly to a trough 43 extending longitudinally of the device, the bottom of which lies beneath the worm 20. Actually, the worm lies and operates in the trough 43 so that the worm must be withdrawn therefrom before the hopper may be removed. The hopper is shown in Figure 2, 3 and 7, but it has been removed in Figure 1 in order that the worm operating mechanism may be seen.

The worm 20 is provided at its inner end with a light wire finger 44 (see Figure 8) which is offset from the axis of the worm so that it rotates around said axis when the worm is rotated. The worm in this figure is shown with an agitator which may or may not be used in the device, as desired. In this alternative, the worm is formed with central, longitudinal passage 45 extending longitudinally thereof, through which a thin rod 46 extends and projects beyond each end thereof. At the inner or smaller end of the worm, the rod is provided with a plurality of resilient fingers or agitators 47 diverging from said rod, while the opposite end of the rod is connected to one end of a resilient arm 48, the opposite end of which is anchored in any desired manner (not shown). The free end of the arm 48 and, consequently the rod 46 with its agitators 47, is reciprocated by one or more cam surfaces 50 located on the outer surface of the contrate gear 23.

An agitator 51, in the form of a blunt blade, is reciprocally mounted in the hopper 42 immediately over the worm 20 at the point where it enters the barrel 17. This agitator extends freely through the wall of the hopper and is connected by a web 52 lying at right angles thereto, to a pitman arm 53 extending parallel to the agitator and slidably mounted in a bracket 54 carried by a support 55 extending from the end support 11 to the support 14 at one side of the worm. The arm 53 is provided at its outer end with a vertical slot 56, see Figure 3, in which an eccentric pin 57 operates, said pin projecting outwardly from the gear 33, so that the rotation of this gear causes the pitman arm and the agitator to reciprocate. The agitator 51 is of such length that when it is in one extreme position, it clears the hopper 42 in order that the latter may be removed.

The apparatus described thus far is adapted to feed tobacco into the barrel 17. To this end, the tobacco is placed in the hopper 42 over the worm 20 in the trough 43. Suitable means, not shown, may be provided for pressing the tobacco downwardly or the operator may press it down with his fingers. When the crank 36 is turned, the worm turns to move tobacco along the trough into the barrel. This tends to pack the tobacco around the comparatively small entrance to the barrel, but the reciprocating agitator 51 assists in breaking up any lump of tobacco which may start to form at said entrance. As the worm continues to work, the tobacco forms substantially a funnel leading to the barrel and the opening in this funnel gradually grows smaller as the tobacco builds up. As the mass of tobacco consists of numerous interwoven strings of tobacco, the turning movement of the worm tends to stretch the strings at one point when the tobacco starts to become a lump at the barrel entrance and finally these stretched strings break suddenly, releasing a mass of tobacco which flies upwardly a little way in the hopper. In other words, the

tobacco seems to build up at the barrel entrance into a somewhat solid mass but the greater part of the mass is hurled away therefrom as described, thus continually freeing the entrance to permit more tobacco to move therethrough.

An endless belt 57, see Figures 1 and 5, having at least one turn around the barrel 17 adjacent its outer end, extends across the machine at an angle to both the barrel and the ends of the machine. Suitable means is provided for drawing the belt around the barrel, such as, for example, a drum 58 positioned in line with the belt at one side of the barrel, the upper surface of the drum being substantially parallel with the upper surface of the barrel. This drum is fixedly mounted on a shaft 60 which is journalled in a support 61 and a standard 62 spaced from the support, said support and standard being substantially parallel to the belt 57. A ratchet-wheel 63 is fixedly mounted on the shaft 60 between the support 61 and the standard 62. The drum 58 is adapted positively to grip the belt and to this end it is provided with a plurality of short pins 64 projecting outwardly from the periphery thereof which stick into the belt as it passes over the drum surface. The drum has a vertical flange 65 projecting outwardly from its surface at the side thereof closest to the feed end 15 of the device. This flange prevents the belt from creeping along the barrel towards the end 15 of the device when the drum is rotated.

At the opposite side of the barrel 17, the belt 57 passes over a suitable bearing 66 lying in substantially the same plane as the top of the barrel. A spring piece 67 extends downwardly from the bearing 66 and its lower or free end tends to spring outwardly so that the belt, which extends over this piece, is kept relatively taut or, in other words, the spring piece 67 takes up any slack in the belt.

As the upper part of the belt 57 on one side of the barrel is not in line with that on the other side thereof, owing to the twist or snub about the barrel, it is necessary to have two spaced vertical pins 68, see Figures 2 and 5, extending upwardly from the base 10, one being in line with the drum 58 and the other in line with the bearing 66 and the spring piece 67. In travelling from the drum to the lower end of the spring piece, the belt moves around one side of the pin in line with the drum and around the opposite side of the other pin.

Suitable means is provided for retaining a roll 70 of relatively narrow cigarette paper which has a gummed edge 71, said roll being held substantially parallel to the belt 57 and in line with the portion of the latter moving over the bearing 66. In the drawings, the roll rests loosely in a receptacle 72 made up of a curved strip of resilient metal 73 forming the bottom and outer end of the receptacle, and a plate 74 on one side thereof, the side of the drum 58 and its flange 65 forming its opposite side. The strip of metal 73 extends inwardly beneath the barrel 17 where it is bent in an easy curve back on itself and anchored at 74' on a brace 75 extending between the supports 14 and 61 above the base 10, see Figures 2 and 5. A strip of paper 76 is drawn from the roll 70 over the metal strip 73 and then along the lower surface of a guide 77. This guide, see Figure 5, extends from a point just above the strip 73 towards the side of the machine opposite to that on which the receptacle 72 is located, and then it is bent in a gradual curve upwardly and over beneath the belt 57 to join a table 78 over which the belt

is moved, this table extending the full length of the machine, as shown in Figure 1. A vertical guide 79 is mounted on the table along side the belt on the side thereof closest to the feed end 15 of the device. The paper follows the guide 77 and passes over the table 78 beneath the belt. If desired, the upper surface of the table may be slotted so that the strip of paper passes through the slot while the belt passes over the surface of the table. The belt presses against the paper adjacent this point and it is the movement of the belt that draws the strip of paper from the roll. As the belt progresses, it draws the strip of paper around the barrel 17 in a spiral, the paper making at least one complete turn around said barrel. The belt applies considerable pressure to the paper since the belt is drawn around the barrel. The angle of the belt and the paper to the barrel is such that the gummed edge of the strip arriving at the barrel overlaps the opposite or free edge of that portion of the strip which has already travelled around the barrel.

Suitable means is provided for moistening the gummed edge of the paper just before it reaches the barrel 17. The gummed edge may be continually moistened but it is preferably intermittently moistened in order to avoid the possibility of weakening the paper with too much moisture. In the illustrated form of the invention, the moistening means consists of a water reservoir 80, see Figure 5, located adjacent the strip of paper 76 and having a wick 81 projecting upwardly therefrom. A notch 82, see Figure 1, is cut in the table 78 to enable the wick to be moved upwardly against the gummed edge of the strip of paper. The water reservoir is removably supported immediately beneath the table by a substantially U-shaped spring bracket 83 the lower arm of which is attached to the reservoir at the bottom thereof, and its upper arm, longer than the lower one, slidably fits into a holder 84 mounted on the table 78. If desired, gripping elements 85 may project upwardly from the top and downwardly from the bottom of the bracket 83 in order to facilitate the removal of the reservoir when it is to be filled with water, there being a covered opening (not shown) formed in the reservoir for this purpose.

A comparatively long shaft 86 extends beneath the barrel 17 at approximately right angles to the belt 57. This shaft is journaled in a bearing 87 carried by the support 14 and has a bevel gear 88 at one end meshing with another bevel gear 90 fixedly mounted on the shaft 28, see Figure 1, while the opposite end of the shaft 86 extends through a bearing in the support 61. A spring finger 91 extends downwardly and inwardly from the reservoir 80 adjacent its outer end, over the shaft 86, and a cam 92 mounted on said shaft, is adapted intermittently to urge the spring finger 91, and consequently, the free end of the reservoir upwardly. This moves the wick 81 upwardly into contact with the gummed edge of the strip of paper 76, the resiliency of the finger 91 preventing the wick from striking the paper too hard.

The drum 58 is rotated in a manner to be described and draws the belt 57 and the strip of paper 76 around the barrel 17. The very great pressure of the belt against the paper on the barrel presses the moistened gummed edge of the paper lying therebeneath during at least one turn around the barrel. This forms a continual spirally-wound tube 93 of cigarette paper, hereinafter called a spiral tube, which is moved off

the end of the barrel by the new paper being continually fed thereto. The tobacco which is moved into the barrel, as previously described, passes therethrough and is injected into the spiral tube 93 as it is formed.

The drum 58 may be rotated in any suitable manner and this rotation is preferably intermittent. The means for rotating the drum is shown in conjunction with means for controlling the pressure of the tobacco in the tube 93.

A clutch disc 94 is fixedly mounted on the shaft 86 beyond the support 61 and in the plane of rotation of the ratchet-wheel 63, see Figure 4. This clutch disc consists of spaced discs 95, best seen in Figure 2, having one or more eccentric pins 96, in this case two, extending therebetween equispaced from each other and from the shaft 86. An arcuate control arm 97 extends upwardly over and clear of the barrel 17 at substantially the same angle thereto as the belt 57. This arm has a downwardly extending radial arm 98 at its inner end, which is freely mounted on the shaft 60 between the support 61 and the ratchet-wheel 63, and at its opposite end the control arm 25 curves over and around the outer edge of the clutch disc 94 but it is spaced from said edge and terminates adjacent the bottom of the disc. A slightly tapered tube 100 is mounted on the outer end of the control arm 97 and points inwardly and upwardly towards the clutch disc. A pointed pin 101 extends outwardly from the inner end of the tube 100 into the space between the discs 95 and terminates at a point adjacent the bottom of the circular path of the pins 96. A curved 30 spring 102 extends from the arm 97 into the outer end of the tube 100 to press the pin 101 into its extreme outermost position. A pawl 103 is pivotally mounted on the control arm 97 at the radial arm 98, said pawl being adapted to 35 engage the teeth of the ratchet-wheel 63 to turn said wheel 63 to the left in Figure 4 when the outer end of the control arm 97 is raised upwardly, and to move over a deflector shelf 104 projecting outwardly from the support 61 over the ratchet-wheel, when the outer end of the control arm is dropped downwardly. Another 40 pawl 105 extending upwardly from the base 10, engages the teeth of the ratchet-wheel in order to prevent it from being turned to the right in 45 Figure 4.

A finger gauge 106 is mounted on the control arm 97 between the ends thereof. This finger gauge consists of a vertical rod 107 having a head 108 at its lower end. The rod 106 is bent 50 at its upper end over and along the upper edge of the control arm to form a horizontal rod 110. Just as the rod 107, the rod 110 is normally spaced above the control arm but the horizontal rod is bent downwardly towards the arm until its opposite end touches the control arm where it is connected thereto in any suitable manner. As the upper edge of the control arm is curved, the natural tendency of the free end of the horizontal rod is to remain above the arm. A slide 55 111 operating on tracks 112 on each side of the control arm at the upper edge thereof, lies over the control rod 110 and when this slide is moved towards the free end of the horizontal rod, the latter is drawn or bent downwardly and, consequently, the vertical rod 107 and its head 108 are moved downwardly. In other words, the position of the finger gauge in relation to the control arm may be adjusted by moving the slide arm 60 111 back and forth over the rod 110.

The finger gauge 106 rests on the filled spiral

tube 93 and holds up the outer end of the control arm 97. When the pressure of the tobacco in the tube reaches the required point, the control arm is held in such a position that the tip of the pin 101 lies in the path of the pins 95 of the clutch disc 94. When a pin 96 comes around, it engages the tip of the pin 101 and begins to move the latter pin and the outer end of the control arm upwardly. As the pin 96 continues along its circular course, it first moves along the pin 101 towards the control arm, thus magnifying the engagement of the two pins to ensure a positive grip therebetween. As the pin 96 further continues its course, it recedes from the control arm and finally disengages the pin 101 to permit the control arm to drop downwardly until the next pin 96 engages the pin 101. During the first part of the upward movement of the control arm, the ratchet-wheel 63 remains stationary while the pawl 103 moves off the deflector shelf 104 but during the latter part of said movement, the pawl engages the teeth of the ratchet-wheel to turn the latter, which, in turn, rotates the drum 58.

When the pressure of the tobacco in the tube 93 is not sufficient, the finger gauge 106 presses the wall of the tube downwardly, thus permitting the control arm to drop downwardly to move the pin 101 out of the path of the pins 95. This condition remains until the pressure of the tobacco in the tube is great enough to raise the finger gauge and the control arm upwardly to return the pin 101 into the path of the fingers 96. The ratchet-wheel 63 and the drum 58 remain stationary when the pressure of the tobacco in the tube 93 is below a predetermined point. The desired pressure of this tobacco may be regulated by moving the slide 111 along the control arm to raise or lower the finger gauge in relation to said arm, the lower said gauge is the lower the pressure required in the tube 93 to set the drum 58 into motion and vice versa.

At a point spaced from the discharge end of the barrel 17 and at the discharge end of the base 10, there is a frame 113 supported at one side above the base by a post 114 and at the other side by a web 115 which is connected to the support 61. The frame 113 consists of spaced plates 116 between which a knife 117 is pivotally mounted. A short tube 118 extends inwardly from the frame 113 in line with the barrel 17, said tube flaring outwardly towards its free end, as at 119. A circular opening 120 is formed in the outer plate 116 in line with the tube 118, the diameter of this opening of said tube where it joins the frame is only slightly larger than that of an ordinary cigarette. The knife 117 consists of a substantially rectangular holder 121, see Figures 1 and 6, pivotally mounted at its upper and outer corner upon a pivot pin 122 which removably extends through the frame 113 at the upper corner thereof on the same side of the machine as the drum 58. A blade 123 is removably held by the holder 121 and extends outwardly from the bottom thereof at right angles thereto. This blade is preferably very thin and sharp and it may be a portion of a razor blade. A vertical connecting rod 124 is loosely journaled at its lower end in a long vertical bearing 125 mounted on the base 10. The upper end of this connecting rod is bent over to form a finger 126 which extends through the holder 121 at the top thereof and at a point spaced inwardly from the pivot pin 122. A wire spring 127, see Figure 6, is anchored at one end of the

frame 113, at 128, on the inner surface thereof and extends across the frame beneath the finger 126. This spring holds the connecting rod 124 in its uppermost position and it normally retains the blade 123 at an angle above the opening 120 and the point where the tube 118 connects with the frame 113, as shown in broken lines in Figure 6.

The support 61 is cut away to form a recess 130 adjacent the connecting rod 124, see Figure 4, and an anvil 131 loosely mounted on said connecting rod, rests on a shoulder 132 formed on the rod. The anvil projects outwardly from the rod and extends through the recess 130 just beyond the support 61, where it is provided with a loop 133. An arm 134 is pivotally mounted at its upper end at the upper edge of the support 61 on the side thereof adjacent the drum 58 and this arm is pressed by a spring 135 against a cam surface 136 formed on the side of the drum 58, see Figure 5, said surface having a cam 137 projecting outwardly therefrom. A very light wire spring 138 extends outwardly and downwardly from the upper end of the arm 134 and passes through the loop 133 of the anvil 131. An arcuate lever 140 extends outwardly and downwardly from the end of the control arm 97 adjacent the drum 58 and this arm normally passes over and down beside the anvil 131, see Figure 4. When the cam 137 moves the free or lower end of the arm 134 outwardly, the light spring 138 causes the anvil 131 to pivot into a position in the path of the lever 140. Actually, at the time the drum 58 is rotated by the control arm 97, the lever 140 has been moved down past the anvil and it is at this time that the arm 134 causes the anvil to pivot. Therefore, the anvil swings against the lever but the pressure of the spring 138 is not sufficient to interfere with the movement of the lever and then the anvil pivots into the path of the lever when the latter is out of the way. In the meantime, the cam retains the arm 134 out of its normal position until the next movement of the drum which takes place when the control arm is next raised. This time the lever strikes the anvil and pushes it and the connecting rod 124 downwardly. This movement draws the blade 123 of the knife 117 downwardly so that the blade cuts through that part of the filled spiral tube 93 which is extending through the tube 118 and the frame 113. A standard 141 having a sloping upper surface 142, is mounted on the base 10 and as this surface lies in the path of the anvil 131 when it is moved downwardly, the surface causes the anvil to pivot back to its normal position, this being possible since the cam 137 has by this time released the arm 134.

In use, tobacco is placed in the hopper 42 and the crank 36 is turned to the right. The worm 20 injects tobacco into the barrel 17 in the manner described and this tobacco is pressed on through the barrel into the spiral tube 93. It will be noted that the knife 117 is spaced from the end of the barrel. This is done so that there is sufficient tobacco in the tube to set up enough resistance to prevent said tobacco from being pushed right through the tube. The worm 20 turns in the same direction as the tube 93, thus neutralizing any tendency the tobacco may have of packing in the tube in a spiral. As the worm is tapered, the pressure is exerted by it against the tobacco gradually diminishes as the latter moves through the barrel. Toward the end of the worm, the tobacco is moved more or less only

at the centre of the barrel so that pressure is built up from the centre outwardly towards the sides.

The finger 44 on the end of the worm, rotates in the tobacco within the barrel to prevent said tobacco from packing too solidly or in lumps by stirring it up before entering the tube. If the agitator shown in Figure 8 is used, the rod 46 is reciprocated in the worm and consequently the resilient fingers or agitators 47 are also reciprocated. When the agitators 47 are drawn towards the worm, the pressure of the tobacco causes them to collapse together so that they offer very little resistance to the movement of the tobacco, but when the agitators are moved away from the worm, their free ends spread outwardly and press the tobacco on through the barrel 17. These agitators reach the tobacco near the walls of the barrel so that it is moved along with that at the centre of the barrel, said latter tobacco being moved by the worm.

The turning of the crank 36 also rotates the clutch disc 94 which, when the pressure of the tobacco in the cigarette reaches a predetermined point, raises the free end of the control arm 97 to cause said arm to rotate the drum 58. This drum, in turn, draws the belt 57 and consequently the strip of paper 76 around the barrel 17 to form the spiral tube 93. This tube fills with tobacco and moves on into the tube 118 of the frame 113. At predetermined intervals, the knife 117 is operated to cut off a desired length of cigarette. The mounting of the blade 123 causes the latter to move both downwardly and across the filled tube 93 which results in a nice clean cut.

It is pointed out that the anvil 131 is moved out of its normal position when the drum 58 is in motion. This means that the anvil assumes a position in the path of the lever 140 when the control arm 97 is in its lowermost position. As soon as the free end of the arm is raised again, the lever presses the anvil downwardly and this causes the knife 117 to cut through the filled tube 93, but the drum 58 does not rotate during the first part of the movement of said arm, since the pawl 103 must move off the deflector shelf 104, and therefore, the tube 93 is stationary when the knife cuts through it.

As the crank 36 is turned, the drum 58 remains stationary if the tobacco in the spiral tube is not packed tight enough. This is due to the fact that the finger gauge 106 has permitted the free end of the control arm to drop down so far that the pin 101 clears the eccentric pins 96. This condition remains until the tobacco in the spiral tube builds up sufficient pressure to raise the finger gauge sufficiently to move the point of the pin 101 into the path of the pins 96.

The wick 81 of the water reservoir 80 moistens the gummed edge of the strip of paper 76 as it passes thereover. The setting of the cam 92 is such that the wick is held away from the paper when the crank 36 is at rest in a vertical position, as this is the position the crank is naturally left in when the operator is through with the machine. This prevents the paper from becoming too moist when the machine is at rest.

This machine is so designed that one rotation of the drum 58 moves the tube 93 forwardly a distance equal to the length of a conventional cigarette. This distance of movement is dependent upon the size of the drum, the width of the paper, and the angle at which the belt 57 is set in relation to the barrel 17. It is to be under-

stood that the machine may be designed to turn out cigarettes of any desired length. Furthermore, the knife 117 and its associated elements might be omitted altogether and the cigarettes cut off from the spiral tube in any desirable manner by the operator of the machine.

The mechanism shown in the drawings may be enclosed within a suitable casing, but this has been omitted for the sake of clarity.

10 While a crank 36 has been shown, it is to be understood that a small motor may be connected to the shaft 34 so that the machine would be power driven. This device is primarily designed for home use but, if desired, it may be built any required size for commercial usage.

15 The cigarettes turned out by this machine are evenly packed and they have the appearance and structure equal to that of commercially manufactured cigarettes. The spiral winding of the tube 93 permits tobacco to be injected thereinto under pressure without bursting open the seams. This is due to the fact that lateral pressure does not press against any seam which would be the case with ordinary cigarettes having one longitudinal seam.

20 25 This machine turns out cigarettes in an easy and rapid manner. It reduces the cost of smoking since it gives the smoker all the advantages of a hand rolled cigarette together with the appearance and structure of a manufactured cigarette. This means that many people will be able to make their own cigarettes who could not roll their own or who were unable to make a decent looking cigarette on their own. There are numerous devices on the market for assisting in making hand-made cigarettes, but cigarettes made in this manner never look well made and they obviously look home made. This machine may be set to produce a fairly loosely packed cigarette or anything up to a tightly packed one,

30 35 40 45 in accordance with the operator's desire and any type of tobacco may be used therein. When pure tobacco is used, the cigarettes produced do not include the foreign substances which are introduced into manufactured cigarettes. Finally, this machine is neat, compact, relatively simple in construction and it may be very easily operated.

Various modifications may be made in this invention without departing from the spirit thereof or the scope of the claims and, therefore, the exact forms shown are to be taken as illustrative only and not in a limiting sense, and it is desired that only such limitations shall be placed thereon as are disclosed in the prior art or are set forth in the accompanying claims.

What I claim as my invention is:

1. A cigarette machine comprising a base, a barrel supported above the base, the diameter of said barrel being substantially equal to that of a cigarette, an endless belt having at least one turn around the barrel, means for holding a strip of narrow gummed cigarette paper in the machine, means for moistening the gummed edge of the paper, said paper extending around the barrel at least one complete turn with its gummed edge overlapping the free edge thereof beneath the belt, means for intermittently drawing the belt around the barrel to move the paper therearound under pressure to form a spiral tube, said tube being moved off the barrel, and means for injecting tobacco into the tube during both the moving and stationary periods of the belt.

2. A cigarette machine comprising a base, a barrel supported above the base, the diameter of said

barrel being substantially equal to that of a cigarette, an endless belt having at least one turn around the barrel, means for holding a strip of narrow gummed cigarette paper in the machine, means for moistening the gummed edge of the paper, said paper extending around the barrel at least one complete turn with its gummed edge overlapping the free edge thereof beneath the belt, a drum at one side of the barrel, over which the belt extends, means for intermittently rotating the drum to draw the belt around the barrel to move the paper therearound under pressure to form a spiral tube, said tube being moved off the barrel, and means for injecting tobacco through the barrel into the tube during both the moving and stationary periods of the belt.

3. A cigarette machine comprising a base, a barrel supported above the base, the diameter of said barrel being substantially equal to that of a cigarette, an endless belt having at least one turn around the barrel, means for holding a strip of narrow gummed cigarette paper in the machine, means for moistening the gummed edge of the paper, said paper extending around the barrel at least one complete turn with its gummed edge overlapping the free edge thereof beneath the belt, a drum at one side of the barrel, a bearing at the other side of the barrel, said belt extending around the drum and the bearing, means on the drum for positively gripping the belt, means for intermittently rotating the drum to draw the belt around the barrel to move the paper therearound under pressure to form a spiral tube, means for injecting tobacco through the barrel into the tube, and means for cutting the filled tube into desired lengths, said cutting means operating when the drum is at rest.

4. A cigarette machine comprising a base, means on the base for holding a strip of narrow gummed cigarette paper, means for forming said paper into a continuous tube and intermittently moving said tube forwardly in the machine, means for injecting tobacco into the tube during both the moving and stationary periods of the tube, a finger gauge connected to the moving means and adapted to bear against the filled tube, said gauge causing the moving means to operate when the pressure of the tobacco in the tube reaches a predetermined point and preventing said operation when the pressure drops below said point.

5. A device according to claim 2 in which the means for intermittently rotating the drum comprises a ratchet-wheel connected to the drum, a pawl adapted to engage the ratchet-wheel, and means for reciprocating the pawl intermittently to rotate the ratchet-wheel and the drum.

6. A device according to claim 2 in which the means for intermittently rotating the drum comprises a control arm pivotally mounted at one end thereof on the base, a ratchet-wheel connected to the drum, a pawl mounted on the control arm adjacent its pivot, said pawl being adapted to engage the ratchet-wheel, a clutch disc supported adjacent the free end of the control arm, means for rotating the clutch disc, and means on the clutch disc for intermittently raising and releasing the free end of the control arm to pivot said arm intermittently to rotate the ratchet-wheel and the drum.

7. A device according to claim 2 in which the means for intermittently rotating the drum comprises a control arm pivotally mounted at one end thereof on the base, a ratchet-wheel connected to the drum, a pawl mounted on the control arm

adjacent its pivot, said pawl being adapted to engage the ratchet-wheel, a clutch disc supported adjacent the free end of the control arm, means for rotating the clutch disc, at least one pin eccentrically mounted on the clutch disc, and a pin mounted on the free end of the control arm normally projecting into the path of the eccentric pin, said clutch pin intermittently engaging the pin of the control arm to raise the free end thereof to pivot said arm intermittently to rotate the ratchet-wheel and the drum.

8. A device according to claim 2 in which the means for intermittently rotating the drum comprises a control arm mounted at one end thereof on the base, a ratchet-wheel connected to the drum, a pawl mounted on the control arm adjacent its pivot, said pawl being adapted to engage the ratchet-wheel, a clutch adjacent the free end of the control arm for intermittently raising said end, and a finger gauge mounted on the control arm adapted to rest on the filled spiral tube, said gauge causing the control arm end to engage the clutch when the pressure of the tobacco in the tube reaches a predetermined point to raise said end and to disengage the clutch when the pressure drops below said point.

9. A device according to claim 2 in which the means for intermittently rotating the drum comprises a control arm pivotally mounted at one end thereof on the base, a ratchet-wheel connected to the drum, a pawl mounted on the control arm adjacent its pivot, said pawl being adapted to engage the ratchet-wheel, a clutch disc supported adjacent the free end of the control arm, means for rotating the clutch-disc, at least one pin eccentrically mounted on the clutch disc, a pin mounted on the free end of the control arm extending towards the clutch disc, and a finger gauge mounted on the control arm adapted to rest on the filled spiral tube, said gauge retaining the control arm in a position with its pin projecting into the path of the clutch pin when the pressure of the tobacco in the tube reaches a predetermined point and causing the arm to move its pin out of said path when the pressure drops below said point.

10. A cigarette machine comprising a base, means for moistening the gummed edge of a continuous strip of cigarette paper, means for forming a continuous spiral tube from the paper and intermittently moving said tube forwardly in the machine, means for injecting tobacco into the tube, a knife normally resting adjacent the filled tube, and means for moving the blade of said knife through the filled tube at predetermined intervals when the tube is stationary to cut said tube into desired lengths.

11. A device according to claim 1, including a drum over which the belt extends, means for intermittently rotating the drum to draw the belt and paper around the barrel, a knife normally resting adjacent the filled tube, and means operated by the drum rotating means for moving the blade of said knife through the filled tube at predetermined intervals when the tube is stationary to cut said tube into desired lengths.

12. A device according to claim 2, including a ratchet connected to the drum, a control arm pivotally mounted at one end adjacent the ratchet, means for reciprocating the arm to operate the ratchet and rotate the drum to draw the belt and paper around the barrel, a lever mounted on the control arm, an anvil pivotally mounted near the lever, a knife normally resting adjacent the filled tube, said knife being connected to the

anvil, a cam mounted on the drum, and means operated by the cam for moving the anvil into the path of the lever, said lever moving the anvil to move the blade of the knife through the filled tube at predetermined intervals to cut said tube into desired lengths.

13. A cigarette machine comprising a base, means for holding a strip of narrow cigarette paper, said paper being gummed along an edge thereof, means for forming a continuous spiral tube from the paper, a water reservoir movably mounted on the base adjacent the strip of paper, a wick projecting outwardly from the reservoir, means for intermittently moving the reservoir towards the paper to bring the wick into contact with the gummed edge thereof before it is formed into the spiral tube, and means for injecting tobacco into the tube.

14. A cigarette machine comprising a base, a barrel supported above the base, the diameter of said barrel being substantially equal to that of the cigarette, means for forming a tube of cigarette paper around the barrel and discharging said tube off one end thereof, a hopper mounted on the base adapted to receive tobacco, a trough formed in the bottom of the hopper and communicating with the opposite end of the barrel, a tapered worm mounted in the trough with its smaller end extending into the barrel, means for rotating the worm to inject tobacco through the barrel into the tube, a central longitudinal passage extending through the worm, a rod extending through said passage beyond each end thereof, a plurality of resilient agitators diverging from the inner end of the rod, and means at the outer end of the rod for reciprocating the latter as the worm is rotated.

15. A cigarette machine comprising a base, a barrel supported above the base, the diameter of said barrel being substantially equal to that of a cigarette, means for forming a tube of cigarette paper around the barrel and discharging said tube off one end thereof, a hopper communicating with the opposite end of the barrel, said hopper being adapted to receive tobacco, a worm mounted in the bottom of the hopper and extending into the barrel, means for rotating the worm to inject tobacco through the barrel into the tube, an agitator extending into the hopper through one end thereof adjacent the worm at the barrel entrance, and means for reciprocating the agitator in the hopper in a direction parallel to the axis of the worm to prevent tobacco from jamming in the barrel entrance.

16. A device according to claim 2 in which the means for intermittently rotating the drum comprises a control arm mounted at one end thereof on the base, a ratchet-wheel connected to the drum, a pawl mounted on the control arm adjacent its pivot, said pawl being adapted to engage the ratchet-wheel, a clutch adjacent the free end of the control arm for intermittently raising said end, a finger gauge mounted on the control arm adapted to rest on the filled spiral tube, and means for adjusting the position of the finger gauge in relation to the control arm, said gauge causing the control arm end to engage the clutch when the pressure of the tobacco in the tube reaches a predetermined point to raise said end and to disengage the clutch when the pressure drops below said point.

17. A cigarette machine comprising a base, a barrel supported above the base, the diameter of said barrel being substantially equal to that of a cigarette, an endless belt having at least one

turn around the barrel, means for holding a strip of narrow cigarette paper in the machine, said paper being gummed along an edge thereof, a water reservoir movably mounted on the base adjacent the strip of paper, a wick projecting outwardly from the reservoir, means for intermittently moving the reservoir towards the paper to bring the wick into contact with the gummed edge thereof, said paper extending around the barrel at least one complete turn beneath the belt with its gummed edge overlapping the free edge thereof beneath the belt, a drum at one side of the barrel over which the belt extends, means for intermittently rotating the drum to draw the belt around the barrel to move the paper therearound under pressure to form a spiral tube, said tube being moved off the barrel, and means for injecting tobacco through the barrel into the tube.

20. 18. A cigarette machine comprising a base, a barrel supported above the base, the diameter of said barrel being substantially equal to that of a cigarette, means on the base for moistening the gummed edge of a narrow continuous strip of cigarette paper, means for forming a continuous spiral tube from the paper around the barrel, means for intermittently moving the tube off the barrel, means for injecting tobacco into the tube, a knife normally resting adjacent the filled tube, and means for moving the knife through the filled tube at predetermined intervals when said tube is stationary.

19. A cigarette machine comprising a base, a barrel supported above the base, the diameter of said barrel being substantially equal to that of a cigarette, an endless belt having at least one turn around the barrel, means for holding a strip of narrow gummed cigarette paper in the machine, means for moistening the gummed edge of the paper, said paper extending around the barrel at least one complete turn with its gummed edge overlapping the free edge thereof beneath the belt, a drum at one side of the barrel over which the belt extends, means for intermittently rotating the drum to draw the belt around the barrel to move the paper therearound under pressure to form a spiral tube, said tube being intermittently moved off the barrel, means for injecting tobacco into the tube, a knife normally resting adjacent the filled tube, and means for moving the knife through the filled tube at predetermined intervals when said tube is stationary.

20. A cigarette machine comprising a base, a barrel supported above the base, the diameter of said barrel being substantially equal to that of a cigarette, an endless belt having at least one turn around the barrel, means for holding a strip of narrow gummed cigarette paper in the machine, means for moistening the gummed edge of the paper, said paper extending around the barrel at least one complete turn with its gummed edge overlapping the free edge thereof beneath the belt, means for intermittently drawing the belt around the barrel to move the paper therearound under pressure to form a spiral tube, said tube being moved off one end of the barrel, a hopper communicating with the opposite end of the barrel, said hopper being adapted to receive tobacco, a worm mounted in the bottom of the hopper and extending into the barrel, means for rotating the worm to inject tobacco through the barrel into the tube, an agitator extending into the hopper adjacent the worm at the barrel entrance, and means for reciprocating the agitator

in the hopper to prevent tobacco from jamming in the barrel entrance.

21. A cigarette machine comprising a base, a barrel supported above the base, the diameter of said barrel being substantially equal to that of a cigarette, an endless belt having at least one turn around the barrel, means for holding a strip of narrow gummed cigarette paper in the machine, means for moistening the gummed edge of the paper, said paper extending around the barrel at least one complete turn with its gummed edge overlapping the free edge thereof beneath the belt, means for drawing the belt around the barrel to move the paper therearound under pres-

sure to form a spiral tube, said tube being moved off one end of the barrel, a hopper communicating with the opposite end of the barrel, said hopper being adapted to receive tobacco, a worm mounted in the bottom of the hopper and extending into the barrel, means for rotating the worm to inject tobacco through the barrel into the tube, a central longitudinal passage extending through the worm, a rod extending through said passage beyond each end thereof, a resilient agitator projecting beyond the inner end of the rod, and means at the outer end of the rod for reciprocating the latter as the worm is rotated.

ERDMAN RUDOLPH HIEBERT.
